UNITED STATES PATENT OFFICE.

ERNEST LEE, OF SPRINGFIELD, ILLINOIS.

ROAD-GRADE.

No. 894,893.

Specification of Letters Patent.

Patented Aug. 4, 1908.

Application filed April 2, 1908. Serial No. 424,819.

To all whom it may concern:

Be it known that I, ERNEST LEE, a citizen of the United States, residing at Springfield, in the county of Sangamon and State of Illinois, have invented a new and useful Road-
5 Grader, of which the following is a specification.

This invention has relation to road graders and it consists in the novel construction and
10 arrangement of its parts as hereinafter shown and described.

The object of the invention is to provide a road grader at its forward edge with a concaved plate adapted to cut the material at
15 the surface of the road and assist in casting the same laterally and a vertically disposed plate at the rear end of the grader for the purpose of packing the surface of the road with the material previously loosened by the
20 plate.

A further object of the invention is to provide a fender plate at the forward portion of the frame of the grader for the purpose of preventing the loosened material from riding
25 up over and upon the frame of the grader.

A still further object of the invention is to provide runners of peculiar configuration and located at the forward portion of the frame of the grader for the purpose of regulating the
30 depth at which the concaved plate will operate in the surface of the road.

Figure 1 is a side elevation of the grader with the parts arranged generally in the form of a rhomboid; and Fig. 2 is a top plan view
35 of the grader arranged oblongular.

The grader consists of the front angle beam 1 and the rear angle beam 2 which are connected together at their upper ends by the channel beams 3 and foot boards 4. The
40 strip of angle iron 5 is attached to the lower forward edge of the front beam 1 and the concaved plate 6 is attached to the upper portion of the front beam 1 and bears at its lower portion against the strip of angle iron
45 5. The fender plate 7 is attached to the forward side of the forward beam 1 and lies between the said beam 1 and the concaved plate 6. The upper portion of the fender plate 7 projects above the channel beams 3
50 and the foot boards 4. The bearings 8 are

located upon the forward portions of the outer channel beams 3 and the runners 9 are pivotally mounted in the said bearings. The upper portions of the said runners lie in planes parallel with the direction in which 55 the beams 3 extend while the lower portions of said runners are twisted into planes at right angles to their upper portions and are curved as at 10. The curved portions 10 of the said runners are adapted to bear upon 60 the surface of the ground. The levers 11 are pivotally attached to the rear end portions of the channel beams 3 and the links 12 pivotally connect the upper ends of the runners with the said levers. The gear segments 13 65 are mounted upon the beams 3 adjacent the levers 11 and the pawl mechanisms 14 are carried by the said levers and are adapted to engage the said gear segments. The seat post 15 is erected upon the intermediate 70 channel beam 3 and the seat 16 is mounted upon the upper end of the said seat post. The end channel beams 3 are provided with clevises 17 to which the draft chain 18 is attached.

The operation of the grader is as follows: It is drawn along the surface of the road at any desired angle by hitching the draft animals at any point along the chain 18. By manipulating the levers 11 the lower ends of the runners 9 may be raised or lowered so as to regulate the depth at which the concaved plate 6 will cut into the surface of the road. The material that is cast up by the plate 6 is prevented from being deposited upon the rear 80 or top portion of the grader by the fender plate 7. The material that is cut or loosened by the plate 6 is packed at the surface of the road by the rear beam 2.

Having described my invention, what I 90 claim as new and desire to secure by Letters Patent is:—

1. A road grader comprising a frame having at its forward edge a cutting plate and at its rear portion a soil packing beam, runners 95 pivotally mounted at the forward portion of the frame and means for swinging the runners to raise or lower the forward portion of the frame.
2. A road grader comprising a frame, run- 100

ners pivotally mounted at the forward portion of the frame and having rearwardly extending curved portions adapted to engage the ground and means for swinging the runners to raise or lower the forward portion of the frame of the grader.

In testimony that I claim the foregoing as

my own, I have hereto affixed my signature in the presence of two witnesses.

ERNEST LEE.
